STRIPPING DEVICE FOR BOBBINS, ESPECIALLY FOR THE WEFT BOBBINS OF LOOMS

Georg Röhl, 1 Haidenschlagweg, Regensburg, Germany

Filed Oct. 1, 1958, Ser. No. 764,624

Claims priority, application Germany Mar. 19, 1958

15 Claims. (Cl. 28—20)

Stripping devices for bobbins or weft carriers are known in which stripping members are reciprocated by a crank mechanism on guides arranged parallel to the axis of the bobbin, and engaged and disengaged with the bobbin by a spring mechanism. These devices are complicated and big machines. They are useful only with bobbins of a special diameter, and, owing to the parallel guiding of the conical bobbin, a small amount of the remaining filling or yarn cannot be entirely stripped off. There are also devices mounted directly on the looms where the yarn remaining on a bobbin is unwound by turning the bobbin.

The present invention provides a simple and strong stripping device, having simple means for adjustment to any diameter and any angle of cone of the bobbin, and furthermore adapted to be mounted directly on the loom. The principal feature of the stripping device embodying the invention is that stripping members or jaws are carried by endless pull means, for instance endless chains. Two endless pull means may be provided for each bobbin at diametrically opposed sides of the latter. These endless chains are simple but strong and adapted to clean the filling from the bobbin along the entire length thereof. The bobbin with the remaining filling is transferred from the ejection point of a shuttle to the stripping device by way of an inclined slide with a guide for the thickened foot of the bobbin. Such guide has a slot above the stripping device with approximately the shape of the spent bobbin with the remaining filling, so that only a spent bobbin can fall through such slot. Owing to the shape of this slot bobbins with full filling are made to pass further along the side into another container. The spent bobbin can fall with its thickened foot uppermost through an enlarged part of the slot into a reception slot of the stripping device arranged exactly under this enlarged part.

The invention is illustrated by way of example in the accompanying drawings wherein:

Fig. 1 is a side view of the loom with the stripping device mounted thereon;

Fig. 2 is a fragmentary front view of the loom having a stripping device according to Fig. 1;

Fig. 3 is a front view of the stripping device on enlarged scale with the protecting casing removed;

Fig. 4 is a sectional view taken along line IV—IV of Fig. 3, and

Fig. 5 is a top view on the stripping device with the protecting casing partly broken away.

On the back wall 1 of the casing of the device there are mounted a pair of upper pivots 2 for chain wheels 4 and a pair of bearing bushes 3' for shafts 3 on which chain wheels 5 are fixed. An endless chain 6 runs around each chain wheel or sprocket 4 and the associated sprocket 5. These endless chains 6 have runs 6' facing one another and moving along guide member 7 provided in their upper and lower parts with oblong holes 9, 10 extending transversely with respect to the axis of the bobbin 8 to be stripped off. Bolts 11, 12 extend through

2

those oblong holes 9, 10 from bars 13 fixed on the back wall 1, and are provided with adjusting nuts 14, 15. By means of these oblong holes the guide members 7 are adapted to be adjusted transversally to the axis of the bobbin. This allows the guide members to be adjusted with respect to the diameter as well as to the angle of cone of the bobbin 8 and to be fixed in the adjusted positions by means of the nuts 14, 15. The bars 13 carry angle pieces 16 through which screws 17 are screwed to bear against guide members 7 and adjust and fix the same.

The endless chains 6 carry stripping jaws 18 for the filling 19 remained on the bobbin 8, and such jaws are guided close to the bobbin 8 while moving along runs 6' for gripping the remaining filling with their projecting claws and cleaning the whole length of the bobbin 8. By suitably adjusting the guide members 7, the complete stripping off and cleaning of the bobbin 8 is ensured.

Fixed to the back ends of the lower shafts 3 are gears 20 of equal size in meshing engagement with one another and thus driving the endless chains 6 in opposite directions (see the arrows) at equal speed. One of the shafts 3 is elongated at its back end and there further carries a pulley 21 driven by a belt 22 from a pulley 23 fixed on the main shaft 24 of the loom 25 (Fig. 1).

The spent bobbins ejected by a working shuttle 26 are accepted by an inclined slide 27 which is provided with a guide 28 for the foot 29 of the bobbin 8. This guide is preferably of rectangular cross-section and the successive spent bobbins move along the guide under the influence of gravity. Through movement along the slide 27, each spent bobbin with its foot directed upward reaches a point immediately above the stripping device where the slide 27 is provided with a slot 30 of approximately the shape of the bobbin. As soon as the bobbin has reached the slot, its tapered end falls into this slot and thereby the thickened foot 29 of the bobbin 8 is lifted out of its guide 28. The bobbin slides down with its foot 29 moving along the slot 30 in the inclined slide until it reaches an enlargement 31 of the slot 30 through which the thickened foot can pass. Thus, each bobbin is made to exit from slide 27 with its foot 29 uppermost.

Below this enlargement 31 is a reception slot 33 defined at its opposite sides by two plates 32 spaced apart by a distance smaller than the diameter of the foot of the bobbin.

Thus, the thickened foot 29 of the spent bobbin is suspended from the plates 32 with the tapered end of the bobbin directed downwardly through the reception slot in perpendicular position.

50 A lever 34 is pivotally mounted on a pin 35 located behind the bobbin 8 on the back wall 1 of the casing and forms a bellcrank lever with a further lever 36 fixedly secured to lever 34. The lever 36 lies in the path of a stop 37 fixed on the chain 6, and is pivoted downwardly 55 against the action of a spring 38 by the action of stop 37 engaging lever 36. Thus the lever 34 is pivoted forwardly and it pushes the bobbin 8 having its foot 29 caught by the reception slot 33, forward out of slot 30 and between cheeks 39 which are displaceable perpendicular to the axis of the bobbin and urged toward each other by a spring 40.

60 The cheeks have the shape of the foot of the bobbin which is provided with the usual guide rings, and thus yieldably hold the foot of the bobbin that has been pushed between the cheeks. Above the runs 6' the cheeks 39 are each provided with a small arcuate recess 41 corresponding to the diameter of the foot of the bobbin for gripping it tightly. When the filling 19 remaining on a bobbin is stripped off by the stripping members 18 and after a new bobbin is caught in the reception slot 33, the lever 34 of the bellcrank lever is rocked forwardly by the stop 37 engaging lever 36, and this new bobbin is

thereby pushed between the cheeks 41 thus pushing the cleaned bobbin into an outlet 42 communicating with a guiding slot 42' in the front wall of the casing and through which the cleaned bobbin falls into a container 43.

A flap 46 hingedly mounted on the back wall at 45 (Fig. 4) is rocked by pins 44 carried by the upper end of the lever 34 and prevent a bobbin from falling behind the lever 34 when the latter is moved forward. A bridge 47 defining the front end of the reception slot 33 is forwardly displaceable against the action of springs 48. This displaceable arrangement of bridge 47 prevents clamping of the bobbins when they fall down during the forward movement of the lever 34. The lever 36 with its spring 38 is protected by a screen 49 fixed on one of the bars 13.

The pivoting points on the pivots 2 and shafts 3 are 15 lubricated by a centralized lubricating system.

Bobbins with full filling cannot pass through the slot 30 and slide down along the inclined slide 27 to the front edge of the latter where they pass into a special container.

What I claim is:

1. A stripping device for removing yarn from a bobbin, said device comprising means for supporting a bobbin from which yarn is to be removed, endless flexible members, means guiding said flexible members for movement of the latter along paths having runs extending along the axis of a bobbin carried by said supporting means, and stripping jaws carried by said endless flexible members to axially remove yarn from a bobbin carried by said supporting means during movement of said jaws along said runs.

2. A stripping device as in claim 1; wherein each of said endless flexible members is in the form of an endless chain.

3. A stripping device as in claim 2; wherein said guiding means for each of the chains includes a guide member extending along said run of the related chain and slidably engaged by the latter, and means adjustably positioning said guide member transversely with respect to the axis of a bobbin carried by said supporting means at spaced apart locations along said run, thereby to accommodate the stripping device for use with bobbins having different diameters and different cone angles.

4. A stripping device as in claim 3; wherein said guide member has elongated holes extending transversely thereof at said spaced apart locations, and said means adjustably positioning the guide member includes fixed bolts extending through said elongated holes and nuts on said bolts for securing the guide member relative to the bolts.

5. A stripping device as in claim 4; wherein said means adjustably positioning said guide member further includes an adjusting screw bearing laterally against said guide member intermediate said locations of the elongated holes so that the nut on one of said bolts can be loosened and said adjusting screw manipulated to angularly displace the guide member about the other of said bolts.

6. A stripping device as in claim 1; wherein said runs of the endless flexible members extend substantially vertically and are spaced laterally apart; and said means for supporting a bobbin includes a pair of cheeks movable laterally toward and away from each other above said runs and adapted to grip the foot of a bobbin between said cheeks so that the bobbin depends from the latter between said runs, and yieldable means urging said cheeks toward each other.

7. A stripping device as in claim 6; wherein said cheeks have arcuate confronting surfaces shaped to conform to the contours of the foot of a bobbin to be held thereby.

8. A stripping device as in claim 6; further comprising

means defining a reception slot in back of said cheeks and opening forwardly between the latter, said reception slot having a width smaller than the diameter of the foot of a bobbin so that the latter may be inserted downwardly into said reception slot with the foot of the bobbin disposed uppermost and slidably supported by said means defining the reception slot.

9. A stripping device as in claim 8; further comprising means disposed in back of said runs at a location intermediate the latter and operative to move a bobbin supported from said means defining the reception slot forwardly along the latter and into the space between said cheeks for gripping of the foot of the bobbin by the latter.

10. A stripping device as in claim 9; wherein said means operative to move a bobbin includes a pivoted lever movable forwardly in a vertical plane from an inoperative position in back of a bobbin suspended from said means defining the reception slot, and means actuated by one of said flexible members for rocking said lever forwardly from said inoperative position.

11. A stripping device as in claim 10; wherein said means for rocking said lever includes a stop projecting from said one flexible member, an actuating arm fixed relative to said lever and projecting forwardly from the latter into the path of movement of said stop along said run of the related flexible member so that said arm is deflected downwardly upon engagement of said stop therewith, and resilient means urging said lever to return to said inoperative position.

12. A stripping device as in claim 10; further comprising a flap pivotally mounted above the upper end of said lever and having its lower edge position disposed in front of said lever so as to deflect each bobbin forwardly of said lever as the bobbin enters said reception slot.

13. A stripping device as in claim 9; wherein said means defining the reception slot includes a bridge extending laterally across the front of the slot, means supporting said bridge for movement toward and away from said reception slot, and yieldable means urging said bridge rearwardly toward the reception slot.

14. A stripping device as in claim 9; further comprising an inclined slide adapted to receive successive bobbins from which yarn is to be removed and extending over said reception slot, said slide having an elongated opening therein above said reception slot and through which spent bobbins can pass into the reception slot.

15. A stripping device as in claim 14; wherein one side of said slide is higher than the other side thereof, and said slide has a guiding member along said one side adapted to receive the foot of a bobbin moving along the slide, said opening extending laterally from said guiding member so that, when a bobbin reaches said opening, the end of the bobbin remote from its foot commences to fall therethrough and the consequent tilting of the bobbin lifts the foot of the latter out of engagement with said guiding member to permit the bobbin to slide along said opening toward said other side of the guiding member, said opening having an enlarged portion through which the foot of the bobbin can pass upon reaching said enlarged portion during sliding of the bobbin along said opening.
